BYPASS ASSEMBLY FOR PACKERS

Dean Hanes, Duncan, Okla., assignor to Halliburton Oil Well Cementing Company, Duncan, Okla.

Application April 27, 1937, Serial No. 139,257

8 Claims. (Cl. 166—1)

This invention relates to oil well equipment, and more particularly to packers and means for setting the same in an oil well and for releasing the same therefrom.

Packers are often placed in an oil well to seal a conduit to the casing or wall of the well. One common use for a packer is to place it on the bottom of a testing tool, as is shown in the patent to Simmons, No. 1,930,987. It is often difficult to properly seat the packer or, after it has been seated, to remove the same from the well, due to the difference in liquid pressures which exist above and below the packer or inside and outside of the conduit to which the packer is connected.

It is an object of the present invention to provide means for equalizing these pressures at suitable times when it is desired to move the packer and at other times to maintain a sealed or closed conduit which can convey liquid from a point beneath the packer into the conduit to which it is connected or which can convey liquid down beneath the packer so that it can be pumped out.

It is another object of the invention to provide a suitable valve arrangement which may be operated by manipulation of the drill stem or conduit and which is capable of performing various functions such as relieving the pressure beneath the packer when it is being seated, enabling the pressures inside and outside of the conduit to equalize while the apparatus is being lowered into the hole and while the packer is being seated, sealing the conduit to enable the packer to be pumped out and conducting a large amount of fluid to a point beneath the packer to aid in pumping it out.

It is still another object of the invention to provide an arrangement adapted to be used in connection with the packer which will enable the fluid pressures to equalize during certain phases of the operation of the tool but which will be capable of effecting a seal so that pump pressure can be applied beneath the packer to aid in lifting the same when it is desired to remove the packer from the well.

Other objects and advantages reside in certain novel features of the arrangement and construction of parts as will be apparent from the following description taken in connection with the accompanying drawing, in which:

Figure 1 is a vertical cross-sectional view of the upper portion of a valve assembly constructed in accordance with the present invention; and

Figure 2 is a vertical cross-sectional view of the lower portion of the valve assembly and the packer of the same apparatus, Figures 1 and 2 being contiguous.

Referring to the drawing in detail, it will be seen that the apparatus includes a collar or sub 11 having a threaded nipple 12 at its upper end. These threads provide means for securing the as-

sembly to a testing tool or to any other suitable device which may be used with the packer. The apparatus of Figures 1 and 2 will, if used with a tester, be connected between the valve of the tester and the packer thereof.

The lower portion of the sub 11 is threaded internally as shown at 13, to provide means for making a connection with similar threads on a mandrel 14 used to actuate suitable valves as will presently be described. The lower surface of the sub 11 is ground to provide a tapered valve seat 15 capable of effecting a seal with a sleeve 16 concentrically disposed around the mandrel 14, but free to have limited longitudinal movement with respect thereto.

The sub may also have an outer sleeve 17 integrally connected therewith as by means of screw threads 18, the sleeve 17 being provided with a number of holes or ports 19 to act as a strainer or a sieve in preventing cuttings or other obstructions from passing inwardly around the valve seat 15.

To prevent the mandrel 14 from rotating with respect to the sleeve 16, a number of flutes or spline members 20 are formed on the outside of the mandrel. These cooperate with spline pins 21 fixed to the sleeve 16.

The lower end of the mandrel 14 is enlarged somewhat as shown at 22, the enlargement having its upper surface ground to act as a valve capable of seating upon the lower end 23 of the sleeve 16 so as to provide a valve at that point when the mandrel is raised relative to the sleeve.

To provide a conduit for the passage of fluid from below the enlarged portion 22 of the mandrel 14 up into the sleeve 16 when the mandrel and sleeve are in the positions shown in Figure 2, and to provide means for connecting the sleeve 16 to the packer, a conduit member 24 is provided. The upper end of the member 24 is screw threaded onto the lower end of the sleeve 16 as shown at 25. The member 24 extends downwardly around the enlarged portion 22 of the mandrel and is screw threaded at its lower end as shown at 26 to provide means for connecting the upper shoe 27 of the packer thereto.

It will be noticed that the inside diameter of the member 24 is slightly larger than the outside diameter of the enlargement 22 of the mandrel so that liquid can pass around the enlargement 22. If desired, the enlargement 22 may be provided with grooves on its outer periphery to enlarge the area for the passage of fluid around the same but if this is done care should be exercised in preventing the grooves from being so deep that the upper surface of the enlargement 22 does not form an effective seal with the surface 23 of the sleeve 16.

The lower end of the mandrel 14 adjacent to or within the enlargement 22 is provided with a

valve of the poppet type but which has a passage of small diameter therethrough to form a choke extending through the stem thereof. This valve unit may consist of a valve seat member 28 5 against which the valve proper 29 is pressed by means of the coil spring 30. The choke is provided in the stem 31 of the valve by providing a bore or passage 32 therein. With this arrangement, fluid can flow upwardly into the inside 10 of the mandrel 14 only at a limited velocity, being confined to passage through the choke bore 32. Upon the pressure within the mandrel 14 being greater than that which exists below the lower end of the same, the valve 29 will open and provide a larger passage for the flow of liquid downwardly.

As mentioned above, the lower end of the member 24 supports the packer. A conical or "rat hole" packer 33 is shown in the drawing, although it will be understood that the tool may be used with a hook wall packer or with any other kind of packer. In the arrangement shown, the packer is supported by a lower shoe 34 mounted on an inner sleeve 35 screw threaded 20 to the lower end of the member 24 as shown at 36.

Referring again to Figure 1, and particularly to the spline pins 21 which are used to prevent the sleeve 16 from rotating on the mandrel 14, 30 it will be seen that one of these pins is illustrated as being equipped with a small relief valve consisting of a ball 37 against which a small coil spring 38 presses to maintain the same seated upon a seat 39 surrounding a bore 40. 35 One or more of the pins 21 may be so equipped and thus provide means for the passage of fluid outwardly from the space between the mandrel 14 and the sleeve 16 when the pressure in this space is greater than that outside of the tool 40 while preventing the flow of fluid in the reverse direction. This relief valve may open when the equalizing valve 15 is closed.

It will thus be seen that there are four distinct valves shown in the assembly. The upper end of the sleeve 16 seats upon the sub 11 at 45 15, this valve forming what will be termed hereinafter an equalizing valve. A second valve is provided between the enlargement 22 of the mandrel 14 and the lower end of the sleeve 16, this 50 valve forming what will be termed hereinafter a pump out valve. The third valve is that which has just been described, being the ball valve 37 in the spline pin 21 and forming what will be termed hereinafter a relief valve. The fourth 55 valve is the poppet valve 29.

To seat and remove a packer from the well with the apparatus just described, the operation may be as follows:

In lowering the apparatus into the hole, the 60 packer 33, the member 24 and sleeve 16 will normally be hanging on the mandrel 14 and the sub 11 so that the pump out valve 23 is closed. The sub 11, mandrel 14 and enlargement 22 support the weight of the packer. Assuming no 65 obstruction is encountered, the apparatus will be moved to the desired location in the well in this position. When an obstruction is encountered or when the packer 33 starts to move into a rat hole at the bottom of the well, the mandrel 70 14 will move downwardly with respect to the packer and the parts will assume the position shown on the drawing, the valve 23 opening and the equalizing valve 15 closing.

In lowering the tool into the hole, since the 75 equalizing valve is normally open, the pressures

in the mandrel, in between the mandrel and the sleeve 16 and outside of the tool, will all be the same.

In pressing the packer into position in the rat hole, force will be transmitted from the sub 11 5 downwardly through the sleeve 16 and the member 24. Since the liquid beneath the packer is practically incompressible and since there is no place for this liquid to go except out into the formation, it is preferable to provide some means 10 for permitting this fluid which will then be under high pressure to escape from beneath the packer. The relief valve 37 serves this purpose, since fluid can flow upwardly through the inner sleeve 35 and the member 24 upwardly around or between the 15 splines 20 and outwardly above the packer through the valve 37. This insures a proper seating of the packer.

Assuming now that the arrangement is used in connection with the testing tool, the valve 20 the testing tool will be opened and a sample of the fluid beneath the packer will flow upwardly into the tester through the conduit means provided by the inner sleeve 35, the choke bore 32, the mandrel 14 and the sub 11. The testing tool 25 valve may then be closed and the packer released from its seat.

To release the packer, the mandrel 14 is lifted, opening the valve 15, allowing mud fluid to move downwardly in between the mandrel 14 and the 30 sleeve 16 so that the pressure is equalized. Unless this is done, it will be necessary to lift the entire column of mud above the packer in order to move the packer upwardly. Since the formation pressure is normally lower than the mud pressure 35 at the bottom of the well, considerable force would be required to move the packer if an equalizing valve were not provided.

Assuming now that even after the pressure has been equalized above and below the packer, the 40 packer is still stuck and cannot be removed by mere strain in the drill pipe, the mandrel may be pulled upwardly and fluid pressure applied beneath the packer. If the apparatus is used in connection with the testing tool it will be necessary to open the testing tool valve in order to apply this pump pressure and the sample which has been taken will be lost but the packer will be released and the test can be run over again.

In pumping out the packer, as mentioned above, 50 tension will be taken in the drill pipe to cause the mandrel to pull up upon the packer as much as possible and this will close the pump out valve 23. If now pressure is applied on the pumps at the surface of the well and fluid forced downwardly through the mandrel, fluid pressure will be exerted below the packer and tend to release the same. Since this force will be additive to the tension in the drill pipe, the provision of this arrangement tends to insure against allowing the 55 packer ever to become stuck so securely in the well that the drill pipe is pulled in two. The provision of the valve 29 enables a large amount of fluid to be pumped downwardly and circulated 60 around the packer in the event it has become stuck and thus cooperates with the pump out valve 23 in removing a stuck packer from the hole. If this valve were not provided all of the 65 fluid pumped around the packer would have to go through the choke bore 32 and this would so retard the passage of fluid as to make it less effective. By pumping a large quantity of fluid, it is sometimes possible to wash out and remove some 70 obstruction which is holding the packer and 75

which could not be removed by the mere application of pressure, either by fluid or strain.

While only one embodiment of the invention is shown and described herein, it is obvious that various changes may be made without departing from the spirit of the invention or the scope of the annexed claims.

I claim:

1. The combination with a packer adapted to be used in effecting a seal in an oil well or the like of an arrangement for setting and releasing the same in the well, said arrangement including a hollow member connected to the packer, a mandrel within the hollow member, a valve arrangement associated with said member and the mandrel, means for closing the valve arrangement when the mandrel is pressed down on said member, means for opening the valve arrangement when the mandrel is partially raised with respect to said member and means for closing the valve arrangement when the mandrel is fully raised with respect to said member whereby fluid under pressure may be passed through said mandrel to exert fluid pressure on the packer to aid in releasing the same.

2. The combination with a packer adapted to be used in effecting a seal in an oil well or the like of an arrangement for setting and releasing the same in the well, said arrangement including a hollow member connected to the packer, a mandrel within the hollow member, an equalizing valve associated with said member and said mandrel means for closing the valve when the mandrel is lowered with respect to the member, means for opening the valve when the mandrel is raised with respect to the member to allow the pressure above and below the packer to become equal, a pump out valve associated with said member and said mandrel, and means for closing the pump out valve when the mandrel is pulled upwardly with respect to said member whereby fluid under pressure may be passed through said mandrel to exert fluid pressure on the packer to aid in releasing the same.

3. The combination with a packer adapted to be used in effecting a seal in an oil well or the like of an arrangement for setting and releasing the same in the well, said arrangement including conduit means for conveying fluid through the packer and an equalizing valve, a pump out valve and a relief valve associated with said conduit means, said equalizing valve being adapted, when open, to enable the pressure above and below the packer to equalize, said pump out valve being adapted, when closed, to enable fluid pressure to be exerted beneath the packer to aid in releasing the same and said relief valve being adapted to enable fluid to flow from a point below the packer to a point above the same when said equalizing valve is closed and when said pump out valve is open.

4. The combination with a packer adapted to be used in effecting a seal in an oil well or the like of an arrangement for setting and releasing the same in the well, said arrangement including conduit means for conveying fluid through the packer and an equalizing valve, a pump out valve and a relief valve associated with said conduit means, said equalizing valve being adapted, when open, to enable the pressure above and below the packer to equalize, said pump out valve being

adapted, when closed, to enable fluid pressure to be exerted beneath the packer to aid in releasing the same, said relief valve being adapted to enable fluid to flow from a point below the packer to a point above the same when said equalizing valve is closed and said pump out valve is open, said pump out valve being adapted, when closed, to prevent flow of liquid through said relief valve.

5. The combination with a packer adapted to be used in effecting a seal in an oil well or the like of an arrangement for setting and releasing the same in the well, said arrangement including conduit means for conveying fluid through the packer and an equalizing valve, a pump out valve, a relief valve, a choke and a choke by-pass valve associated with said conduit means, said equalizing valve being adapted, when open, to enable pressure above and below the packer to equalize, said pump out valve being adapted, when closed, to enable fluid pressure to be exerted beneath said packer to aid in releasing the same, said relief valve being adapted to enable fluid to flow from a point beneath the packer to a point above the same when said equalizing valve is closed and when said pump out valve is open, said choke being adapted to normally restrict flow of fluid through said conduit means and said choke by-pass valve being adapted to permit greater flow of fluid through said conduit means when pumping out the packer.

6. The combination with a packer of a conduit adapted to conduct fluid through the same, a choke in said conduit to restrict upward flow of fluid therethrough, and a by-pass valve associated with said choke to enable fluid to flow downwardly around the choke, the arrangement being such that in releasing the packer from its seat a large amount of fluid may be pumped through said by-pass valve to a point beneath the packer.

7. The combination with a packer of a conduit adapted to conduct fluid through the same, a choke in said conduit to restrict upward flow of fluid therethrough, a by-pass valve associated with said choke to enable fluid to flow downwardly around the choke, the arrangement being such that in releasing the packer from its seat a large amount of fluid may be pumped through said by-pass valve to a point beneath the packer and valve means associated with said conduit adapted, when open, to permit fluid to flow from inside the conduit to the outside thereof, or vice versa, and adapted, when closed, to enable fluid pressure to be applied to a point beneath the packer to aid in pumping out the same.

8. The combination with a packer of conduit means for conducting fluid through the packer and for seating and unseating the packer, valve means in said conduit, means for operating the valve means to permit the pressure of fluid on the inside and outside of said conduit to equalize as the conduit is moved slightly upwardly with respect to the packer as a preliminary to the unseating of the packer and means for closing the valve means as the conduit is moved further upwardly with respect to the packer so that fluid may be pumped through the conduit to exert fluid pressure beneath the packer to aid in unseating the same.
